UNITED STATES PATENT OFFICE

172,352

DRY SHAVER

Arthur Colin Kingham, Crazies Hill, near Wargrave, England, assignor to Rolls Razor Limited, London, England, a British company

Application February 5, 1954, Serial No. 28,861

Claims priority, application Great Britain
January 25, 1954

Term of patent 14 years

(Cl. D22—3)

To all whom it may concern:

Be it known that I, Arthur Colin Kingham, a British subject residing at "Foxsteep," Crazies Hill, near Wargrave, Berkshire, England, have invented a new, original, and ornamental Design for a Dry Shaver, of which the following is a specification, reference being had to the accompanying drawings, forming a part thereof.

I claim:

The ornamental design for a dry shaver, as shown.
